UNITED STATES PATENT OFFICE

MILTON O. SCHUR AND JOHN G. GOSELINK, OF BERLIN, NEW HAMPSHIRE, ASSIGNORS
TO BROWN COMPANY, OF BERLIN, NEW HAMPSHIRE, A CORPORATION OF MAINE

MANUFACTURE OF BENDS FROM STRAIGHT FIBER TUBES

Application filed April 30, 1930. Serial No. 448,550.

This invention relates to the manufacture of bends from straight fiber tubes, and more particularly from tubes which are made by winding a wet web of interfelted cellulose fibers on a mandrel into a wall of the desired thickness. The web may be formed on paper machinery of any suitable type, e. g., a wet or cylinder machine; and the web in wet condition may be delivered from the carrier felt of the machine to the mandrel on which winding is effected under sufficient pressure to produce an interlocking or matting together of the successive convolutions into a substantially uniform wall structure. The tubes are removed from the mandrel in a wet, plastic state, and are then thoroughly dried. Heretofore, if bends were to be made from the tubes, they were dried or dewatered to a moisture content at which they were rigid enough to bear handling and yet sufficiently soft so that with careful manipulation they could be bent to the desired curvature. The bends were then dried, and, as in the case of straight tubes, were impregnated with a suitable waterproofing material, preferably of a thermoplastic nature, such as pitch, which also served to strengthen the fibrous wall and to impart dielectric properties thereto.

In a mill where continuous large scale production is being carried out and there is a progressive flow of tubes through long dryers run on countercurrent principles, the foregoing practice of making bends presents some serious disadvantages. Thus, when substantial quantities of tubes are withdrawn from a dryer, the drying conditions, that is to say, the humidity and temperature conditions in the dryer, may be seriously upset, as the removal of large masses of wet pulp from a given section of the dryer interferes with the counter-current drying conditions in the dryer. The doors of the dryer, when opened for the removal of the wet tubes, allow excessive leakage of fresh air into the dryer, accompanied by a disturbance in the equilibrium humidity conditions of the dryer. Again, if there is an order for a size of bend which is out of stock and which is not then being run on the machines, the operating schedule of the mill must be changed; and

a large excess of straight conduit which is at the time unnecessary must be made for the sake of a comparatively small proportion of bends. It is almost impossible to forecast sufficiently closely the relative sales of 55 straight and curved pieces to avoid the necessity for suddenly changing the mill schedule for the running of bends, even though there may be in stock an excessive quantity of straight impregnated conduit of the desired diameter. 60

It has been proposed, in the past, that in order to prevent the upset of the dryer through the removal of partially dried tubes, the dry tubes be remoistened to the 65 necessary extent and then bent. This expedient, however, necessitates the storage of relatively large quantities of unimpregnated conduit, which is impracticable because conduit in this condition undergoes comparatively rapid weathering. During storage, it absorbs so much moisture that in the subsequent impregnations blisters are generated in the tube wall, as the moisture is expelled from the interior, unless the tubes are redried. 70 The step of redrying, however, would add materially to the expense of manufacture. Further, these tubes, if piled to any material height, tend to become oval or otherwise get 75 out of shape.

In accordance with the present invention, straight fiber tubes are bent to the desired curvature after they have been impregnated, thereby not only eliminating the undesirable interference with the dryer which has heretofore been experienced, but also enabling the filling of orders for bends of any curvature promptly, because of the customary practice to keep large inventories of impregnated straight fiber tubes. In order to effect the bending of impregnated tubes, it is necessary to effect their conversion to a more or less soft and plastic condition. While various methods of softening and plasticization may be employed, it is most practical to bring 95 about this result by submersing the tubes in water until sufficient moisture has been absorbed thereby to render them plastic. Since the impregnated tubes absorb water very slowly under ordinary conditions, the process 100

may be hastened by exerting pressure upon the water, by raising the temperature, or by doing both. The hot water not only hastens the softening of the fibrous structure, rendering it more or less limp, so that it may withstand bending stresses without undergoing rupture, but it softens the pitch or other thermoplastic material used as the waterproofing agent. If it were attempted to stretch a dry mat of fibers beyond a certain comparatively narrow range, tearing or breaking would result, but if the fibrous mass is conditioned by moistening with water, the cellulosic bonding material in the form of gelatinized cellulose between the fibers apparently undergoes a species of peptization, so that when the stretching forces are applied the fibers may slip relative to one another; and greater distortion of the mat is hence possible without actually tearing the mat. Inasmuch as the pitch usually employed for impregnation has a softening point of 140° to 200° F., it is advantageous to heat the water to approximately this temperature range in order to render the pitch plastic. The desired tempering or conditioning of the fibrous wall and a uniform plasticization of the pitch is brought about only if the tubes remain submerged in the water for a sufficient period of time so as to permit the absorption of appreciable quantities of water. In general, water absorption of about 18% to 20% is desirable, which may be realized by treating the pitch-impregnated tubes with water under, say, 50 pounds pressure per square inch for about eight hours at 298° F. Immediately after removing the tubes from the hot water bath, form-maintaining springs may be inserted into the tubes and they may be bent to the desired curvature before losing their plasticity. If desired, however, the springs may be inserted into the tubes before they are subjected to the action of water, in which case forms such as are customarily used for protecting the tube wall need not be employed, as the impregnated wall is of sufficient strength and rigidity to resist deformation during the insertion of the springs. We do not, however, herein claim a method which comprises inserting flexible form-maintaining devices into tubes, bending the tubes to the desired curvature, drying the bent tubes to a rigid condition, and finally removing the form-maintaining devices therefrom, as such a method is fully described in Letters Patent No. 1,602,165, issued October 5, 1926, to Howard Parker.

A preferred method of bending the tubes which constitutes part of the present invention is with the aid of curved springs, this method and the instrumentalities used therein being illustrated on the accompanying drawing, wherein

Figure 1 is a front view of a straight tube 35 assembled with a normally curved, flat spring

before the spring has exerted its bending action.

Figure 2 represents a section through the assembly on the line 2-2 of Figure 1.

Figure 3 is a view similar to Figure 1 but showing the tube in bent condition.

Figure 4 is a front view of only the spring member in its normal, curved condition.

Figure 5 represents a section through the spring on the line 5-5 of Figure 4.

Figure 6 is a view similar to Figure 1 but illustrating the use of a normally curved helical spring as the bending means.

Figure 7 is a view similar to Figure 6 after the tube has been bent.

Figure 8 is a front view of only the helical spring in its normally curved condition.

Referring in detail first to Figure 4 of the drawing, 1 indicates a flat spring which normally has the contour which the inside edge 85 of the bent tube is to assume. The spring may be provided with suitable means for gripping the tube, for which purpose a plurality of spring clips 2 may be secured to the spring at suitably spaced intervals. For instance, three clips may be used, one being at the center and one near each end of the spring. As best shown in Figure 5, the clips are arcuate in form and a transverse section therethrough constitutes an arc of substantially 95 more than 180°, so that the edges 3 of the clips are separated a distance permitting the clips to be sprung over and to embrace a tube while exerting sufficient spring action to maintain the straightened spring up against 100 the tube substantially throughout its length. The assembly of the spring with a straight tube 3 is made by engaging the clips successively with the straight tube, as a result of which the spring becomes straightened out, as 105 shown in Figure 1. The assembly may be made before the impregnated tube is rendered plastic, in which case, as the tube absorbs moisture and becomes plastic, it gradually bends under the influence of the spring until 110 the normal curvature of the axis of the spring is reached, as shown in Figure 3. The same result is, however, attained if the tube is first rendered plastic and the spring then assembled therewith. The clips serve a double 115 function, namely, that of gripping the tube and that of preventing it from undergoing bulging or other deformation as it yields.

When a normally curved helical spring 5, such as shown in Figure 8, is used in lieu of a flat spring, it should be of a diameter very nearly equal to the inside diameter of the tube, so that when it is inserted in straightened out condition inside a tube 6 to effect bending of the tube, as shown in Figure 6, the circularity 125 of the tube will be maintained as the tube bends to the normal curvature of the spring, shown in Figure 7. The spring 5 may be straightened out for insertion into a straight tube, by winding it up on a straight rod or ar- 130

bor to reduce its diameter so that it may be inserted in the tube, and then releasing it so that its convolutions will expand against the inner wall of the tube and exert the desired bending stresses on the tube. It is thus seen that by using properly shaped springs and assembling them with the straight tubes as described, the bending forces are automatically applied to the tube uniformly and steadily, and the danger of rupturing the tubes by too rapid bending is avoided. The tubes yield gradually and uniformly to the bending forces at a rate which is determined by their plasticity, so that too rapid bending, which is accompanied by weakening of the fibrous structure, is avoided. This latter objection may arise when a tube is bent by hand or by machinery, as in such case the rate of bending is not controlled by the plasticity of the tube, but depends upon the judgment and skill of the operator. The bending method of the present invention is especially advantageous in the bending of tubes impregnated with pitch or other thermoplastic materials, as in such case the plastic straight tubes are sufficiently strong to resist breakage or undesirable deformation by the tensioned, normally curved springs, and at the same time are sufficiently plastic to yield under the stresses exerted thereupon by the springs, and thus be brought to the normally curved condition of such springs.

The plastic tubes may be dried in their bent condition, and after they have been dried or set to a rigid condition, the springs may be removed therefrom and the tubes subjected to further treatment, if desired, such, for instance, as coating with blown asphalt compositions of the type disclosed in Patent No. 1,714,702, issued May 28, 1929, to Wallace B. Van Arsdel, or in patent application Serial No. 325,651, filed December 12, 1928, by Everett W. Lovering, or in Patent No. 1,751,935, issued March 25, 1930, to Everett W. Lovering and Wallace B. Van Arsdel.

The principles of the present invention, while applicable with especial advantage in the manufacture of bends from pitch-impregnated fiber tubes, may have application in changing the form or shape of other articles which have been impregnated with a thermoplastic waterproofing material, such as pitch.

We claim:

1. A method of bending straight fiber tubes while in a plastic state, which comprises assembling such tubes with normally curved springs in straightened out condition, and permitting the springs to return to their normal curvature and to bend the tubes while they are in plastic state.

2. A method of bending a fiber tube impregnated with thermoplastic material while said tube is in a plastic state, which comprises engaging the tube with a normally curved

spring to exert bending stresses thereon, and maintaining said tube in a plastic state while the tube is being bent under the action of the spring returning to its normal curvature.

In testimony whereof we have affixed our signatures.

MILTON O. SCHUR.
